(57) **CLAIM**

The ornamental design for a nonwoven product having patterned indicia, as shown and described.

DESCRIPTION

FIG. 1 is a top plan view of one embodiment of a nonwoven product having patterned indicia according to the present design;

FIG. 2 is a top plan view of a second embodiment of a nonwoven product having patterned indicia according to the present design; and,

FIG. 3 is a top plan view of a third embodiment of a nonwoven product having patterned indicia according to the present design.

The broken line boundaries form no part of the claimed design.
